MULTIPLE TRANSCONDUCTANCE VACUUM-TUBE AMPLIFIER

Robert L. Freeman, Flushing, N. Y., assignor to
Hazeltine Corporation, a corporation of Delaware

Application October 25, 1939, Serial No. 301,141

7 Claims. (Cl. 179—171)

This invention relates to vacuum-tube amplifiers and more particularly to such amplifiers wherein the nature of operation is such as to provide a negative transconductance in addition to the usual positive transconductance.

As used herein the term "transconductance" is defined as the rate of the change of electron current to a first electrode of a vacuum tube with respect to the voltage of a second electrode thereof when all electrodes, excepting said second electrode, are maintained at constant potentials. When a positive increase in voltage of the second electrode is accompanied by an increase in electron current to the first electrode, the transconductance is "positive"; the transconductance is "negative" when a decrease or negative increase in voltage of the second electrode is accompanied by an increase in electron current to the first electrode.

Heretofore, attempts to increase the amplification of vacuum-tube amplifiers have been limited by circuit factors, such as the power factor of associated windings, and by the characteristics of vacuum tubes, such as the influence of tube self-conductances on the associated circuits, which, in turn, restrict the maximum ratio of the reactance of the circuit to the effective resistance thereof and, thus, the gain of the amplifier.

Conventional amplifiers of the prior art generally utilize only the positive transconductance between the control electrode and anode of a vacuum tube. Also, in the prior art, the "dynatron" or negative resistance characteristic of screen-grid tubes is well known. In the operation of a dynatron, when there is appreciable secondary emission at the anode, there is a relatively restricted region where the anode current increases as the anode voltage is reduced, which represents a negative resistance characteristic. Owing to the unstable, limited, and nonuniform nature of the operation of such tubes, however, attempts to utilize the dynatron as an amplifier have been generally unsatisfactory.

It also has been proposed to use a vacuum tube of the hexode type as an amplifier wherein the electrodes are connected to provide a triode section and a tetrode section in series relation or cascade, but, while high amplification theoretically is obtainable in this way, practical difficulties occur, for example, anode-control electrode feedback in the triode section which tends to cause oscillation. However, since such proposal has not otherwise gone beyond operating the vacuum tube in a normal manner, insofar

as using only positive transconductances are concerned, it has met with little favor and has remained only a theoretical possibility.

It is an object of the invention, therefore, to provide an improved, simple and economical vacuum-tube amplifier which overcomes the limitations heretofore encountered in amplifier design and thereby makes possible higher amplification and, if desired, greater selectivity than was economically possible prior to the invention.

It is a further object of the invention to provide a cascade vacuum-tube amplifier comprising a single vacuum tube wherein a negative transconductance is utilized.

It is a still further object of the invention to provide a vacuum-tube amplifier comprising a vacuum tube having an effective negative anode resistance, which is stable in operation and which may be reproduced with uniformity.

It is another object of the invention to provide an improved push-pull amplifier having an exceptionally high amplification.

In accordance with the invention, there is provided an amplifier comprising a vacuum tube having at least a cathode, a first control electrode, a first anode, a second control electrode, and a second anode. An input circuit is coupled to the cathode and first control electrode. A first output circuit is coupled to the cathode and first anode through a two-terminal impedance network having a substantially uniform resistance over a desired frequency band, while an anode or a second output circuit is coupled to the cathode and second anode, the second output circuit including a load impedance of any suitable nature. The first anode and second control electrode are so coupled together and the vacuum-tube design and operation are such that a negative transconductance exists between said second control electrode and first anode, whereby a negative resistance is reflected across the first output circuit which tends to cancel the resistance thereof and the dynamic first anode-cathode self-resistance. The two-terminal network preferably includes the interelectrode capacitance between the cathode and first anode as well as the interelectrode capacitance between the cathode and second control electrode.

In one form of the invention, the arrangement of the amplifier circuit is such that, by an optimum choice of the value of the uniform resistance of the two-terminal network, together with suitable values of both negative and positive transconductances of the vacuum tube, the sig-

nal-output voltage of the second output circuit is in phase with the signal applied to the input circuit and 180 degrees out of phase with the signal-output voltage of the first output circuit. Between the first control electrode and first anode, as well as between the second control electrode and second anode, there preferably are provided screen-grid means to inhibit energy transfer resulting in undesired feedback in the 10 amplifier.

In another aspect of the invention, a regenerative amplifier is provided comprising a vacuum tube having a cathode, two control electrodes and two anodes; an anode circuit coupled to said 15 cathode and one of said anodes farthest from the cathode, an input circuit coupled to the cathode and the control electrode nearest to the cathode; and an output circuit coupled to the cathode and the other anode through a two-terminal 20 network having a uniform resistance over a desired frequency band; together with feed-back means coupling the other control electrode to said other anode whereby regeneration of the 25 amplifier is obtained by virtue of a negative transconductance between said last-named electrodes.

For a better understanding of the present invention, together with other and further objects thereof, reference is had to the following description taken in connection with the accompanying 30 drawing, and its scope will be pointed out in the appended claims.

Referring to the drawing, Figs. 1 and 2 are circuit diagrams of two embodiments of the vacuum-tube amplifier of the invention; Figs. 1a 35 and 2a are electrical equivalent circuits in a form suitable for analysis; and Fig. 3 is a schematic cross-sectional view of a preferred form of vacuum tube.

Referring to Fig. 1 of the drawing, there is 40 shown an amplifier comprising a vacuum tube 10 having a cathode 11, a first control electrode 12, a first anode 13, a screen grid 14, which may be omitted in certain low-frequency applications, a second control electrode 15, and a second anode 45 16. An input circuit having terminals 17, 17 is coupled to cathode 11 and control electrode 12 through a source of bias voltage, such as a battery 18. An output circuit having output terminals 19, 19' is coupled to anode 13 and cathode 50 11 through a two-terminal impedance network 19 having a substantially uniform resistance over a desired frequency band, this network comprising in its simplest form a resistance shunted by the tube and stray circuit capacitances. The first 55 anode 13, the second anode 16, and screen 14 are supplied with suitable operating potentials from sources indicated as +B₁ and +B₂ and +Sc, respectively, while the second control electrode 15 is connected through a high impedance, 60 such as a resistor 20, to a source of negative-bias potential indicated as -C. Thus, an anode circuit is coupled to the second anode 16 and cathode 11 which includes means whereby a positive potential is applied to the anode 16. The second 65 control electrode 15 and the first anode 13 are coupled by means including a condenser 21. By-pass condensers 22 are provided in the various circuits where needed to by-pass currents at 70 signal frequencies to a common terminal, such as ground.

The design and operation of the vacuum tube 10 are such as to provide a negative transconductance between the second control electrode 15 and the first anode 13; that is, the tube configuration and choice of operating potentials

should be such as to produce sufficient electronic space charge between the positively-biased first anode 13 and the succeeding negatively-biased second control electrode 15 so as to reduce the potential to zero in this space charge region. In 5 the art such space charge condition is known as a virtual cathode. As is well known, there is a negative transconductance from an electrode following a virtual cathode in the tube space path to an electrode preceding it which in this case 10 may be termed g_{15, 13}.

A variation of the potential only of the first anode 13 causes an in-phase variation of the electron current flowing to this said electrode; thus the dynamic self-resistance between the 15 first anode-cathode is a positive resistance of value designated as 1/g₁₃. On the other hand, since g_{15, 13} is generally considerably greater than g₁₃, a like variation of the potentials of both electrodes 13 and 15 causes the variations in current 20 to the first anode 13 to be 180 degrees out of phase with said potential variations. Thus, if the potential variation applied to electrodes 13 and 15 is a periodic voltage designated as E₂, the current I₁₃ flowing to the first anode 13 is 25

$$I_{13} = E_2 g_{13} - E_2 g_{15, 13} = E_2 (g_{13} - g_{15, 13}) \quad (1)$$

wherein the signs of g₁₃ and g_{15, 13} have been taken care of in the equation and thus only absolute values are to be assigned to these quantities. 30

In Fig. 1 it is seen that the signal output potential E₂ developed across network 19 is effectively applied to both electrodes 13 and 15 due 35 to their coupling through condenser 21. Consequently, the circuit arrangement cooperating with the tube presents an effective resistance between the first anode 13 and cathode 11 which is: 40

$$\frac{E_2}{I_{13}} = \frac{1}{g_{13} - g_{15, 13}} \quad (1a)$$

Since g_{15, 13} is normally much greater than g₁₃, we may express this effective resistance as 45 -1/g_{15, 13}. Thus, it is seen that this negative effective resistance is reflected in shunt with network 19 and tends to cancel the actual positive resistance thereof as well as the dynamic self-resistance of the first anode-cathode circuit. 50 That is to say, the amplifier tube 10 has an effective negative first anode resistance. This is useful for obtaining high gain where the output impedance is a uniform pure resistance over the pass band, or for increasing the ratio Q of reactance to 55 resistance of a tuned output circuit which also determines the gain of the system. The arrangement of the second control electrode 15 with relation to the first anode 13, the coupling of these electrodes through condenser 21, and the source 60 of negative-bias potential -C thus comprise means providing a negative transconductance between the second control electrode 15 and the first anode 13 for reflecting a negative resistance across the output circuit of the anode 13 which 65 tends to cancel the actual resistance thereof and the dynamic first anode-cathode self-resistance. The impedance network 19 and the condenser 21 comprise means for deriving a potential from the first anode 13 and for applying it without substantial phase shift and with the same polarity to the second control electrode 15. 70

Referring to Fig. 1a, which is electrically equivalent to Fig. 1 but in a form more suitable for explanation, the operation of the invention 75

may be analyzed as follows: The gain of the amplifier is:

$$A = \frac{E_2}{E_1} = \frac{I_2 R}{E_1} \quad (2)$$

but

$$I_2 = -g_{12, 13} E_1 + g_{15, 13} E_2 - g_{13} E_2$$

or, since

$$g_{13} < g_{15, 13}$$

$$I_2 \approx -g_{12, 13} E_1 + g_{15, 13} E_2 \quad (3)$$

$$I_2 = \frac{-g_{12, 13} E_1}{1 - g_{15, 13} R} \quad (4)$$

so that

$$\frac{E_2}{E_1} = \frac{-g_{12, 13} R}{1 - g_{15, 13} R} \quad (5)$$

In these equations the first subscript of the transconductance symbol g refers to the particular control electrode with respect to which transconductance is measured while the second refers to the output electrode whose current is affected by variations of potential on the control electrode. The other symbols represent the quantities indicated in Fig. 1a except the factor R , which is the uniform resistance presented by output network 19 over the frequency band. The transconductance $g_{15, 13}$ is negative, but the sign has been taken care of in Equation 3 so that absolute values are to be inserted in Equation 5.

Now Equation 5 may be viewed as the gain equation for a conventional amplifier whose gain is $-g_{12, 13} R_{\text{eff}}$ where R_{eff} is the effective resistance of the parallel combination of resistance R and $-1/g_{15, 13}$. Thus, the amplifier, when viewed as a conventional amplifier, has a negative anode resistance of a value equal to $-1/g_{15, 13}$. The gain becomes very large as $g_{15, 13} R$ approaches unity. If this product equals or exceeds unity, unwanted oscillations will result.

Successful operation of the amplifier requires that the circuit conditions be such that a virtual cathode, as pointed out above in detail, is formed between anode 13 and control electrode 15 in order to obtain a negative transconductance therebetween. Under conventional triode operation of a tube of the configuration of electrodes 11, 12, and 13, the gain $g_{12, 13}$ would be small, since in this region electrons flow in one direction only and those intercepted by the anode 13 are proportional to the ratio of its intercepting area to the cross-sectional area of the electron path. When a virtual cathode is present, however, most of the electrons returned from the virtual cathode are collected by the anode 13, thus making $g_{12, 13}$ large.

In simplest form the output network 19 consists of a resistance R shunted by unavoidable interelectrode and stray circuit capacitance. An expression for gain in this case is obtained in the same manner as Equation 5 by assuming the output admittance to consist of a conductance $1/R$ and a susceptance $j\omega C$. Then

$$A = \frac{-g_{12, 13}}{\sqrt{(1/R - g_{15, 13})^2 + (\omega C)^2}} \angle \tan^{-1} \frac{\omega C}{(1/R - g_{15, 13})} \quad (6)$$

This may be compared to the gain of a conventional amplifier having the same load admittance which gain is given by the expression:

$$A = \frac{-g_{12, 13}}{\sqrt{(1/R)^2 + (\omega C)^2}} \angle \tan^{-1} \frac{\omega C}{1/R} \quad (7)$$

In conventional broad-band amplifiers, the output circuit consists of a filter network which includes the tube capacitance as an element and which provides an input or transfer impedance

which is approximately uniform over the pass band. To adapt the circuit of Fig. 1a to broad-band usage, the two-terminal impedance network 19 is used. This network must include the tube capacitance as an element and provide an approximately uniform resistance over the pass band.

Referring to Fig. 2, there is shown a single tube cascade amplifier embodying the amplifier of Fig. 1 as the first stage thereof, similar elements having identical reference numerals. A load 23, comprising an impedance Z , is included in the second output circuit of the amplifier, while a screen grid 24 is disposed between control electrode 15 and the anode 16 in addition to the screen grid 14 between the anode 13 and control grid 12. Regeneration is obtained by feed-back means comprising the condenser 21 coupling the control electrode 15, acting as a control electrode of a first stage of amplification, directly to the first anode 13 of the same stage, as in the arrangement of Fig. 1. Thus, as further pointed out below in connection with the analysis of Fig. 2a, over the frequency band in which the impedance network 19 of the first stage is of uniform resistance, the effective overall transconductance of the system can be made very large and substantially independent of the nature of the final output impedance 23. Furthermore, the final output voltage is in phase with the input voltage while the output voltages of the first and second output circuits are 180 degrees out of phase, thereby providing a "push-pull" output with high amplification suitable for the audio-frequency amplification stage of a modulated signal receiver.

In Fig. 2a is shown an electrical equivalent of the circuit of Fig. 2 which is the same as that of Fig. 1a except that load 23 comprising impedance Z is incorporated in the second output circuit. This impedance Z has a negligible effect on the operation of the first part of the circuit since the transadmittance between the anode 16 and the first three electrodes is made negligible by suitably constructing and operating the screen grid 24.

The gain of the amplifier of Figs. 2 and 2a is:

$$A = \frac{E_p}{E_1} = \frac{I_p Z}{E_1} \quad (8)$$

and

$$I_p = -g_{12, 16} E_1 - (g_{13, 16} + g_{15, 16}) E_2 \quad (9)$$

where the symbols for transconductance are as explained above, and the symbols for the other quantities are as indicated on Fig. 2a. Using Equation 5 to express E_2 in terms of E_1 and substituting this expression for E_2 in Equation 9, we get:

$$I_p = -g_{12, 16} E_1 + \frac{(g_{13, 16} + g_{15, 16}) g_{12, 13} R E_1}{(1 - g_{15, 13} R)} \quad (10)$$

Thus,

$$\frac{E_p}{E_1} = \left[-g_{12, 16} + \frac{(g_{13, 16} + g_{15, 16}) g_{12, 13} R}{1 - g_{15, 13} R} \right] Z \quad (11)$$

From Equation 5 it is seen that voltages E_1 and E_2 are in phase opposition and might nullify each other in their influence on the second anode current. However, the influence of E_2 is made to predominate. That is to say, the second term in the bracket of Equation 11 is made much greater than the first by suitable choice of the value of resistance R and control of the values of the various transconductances by suitable tube design and operating potentials. Measurements on existing tubes indicate that $g_{13, 16}$ is always

small and, when a virtual cathode exists, $g_{12, 16}$ is usually small compared with the second term within the bracket of Equation 11. Thus Equation 11 may be written in approximate form:

$$5 \quad \frac{E_p}{E_1} = \left(\frac{g_{12, 13} R}{1 - g_{15, 13} R} \right) (g_{15, 16} Z) \quad (12)$$

which shows clearly the operation is effectively that of two amplifiers in cascade, the gain of each being given by the separate quantities in parentheses.

The transconductances $g_{12, 13}$, $g_{15, 13}$, and $g_{15, 16}$ are usually comparable in magnitude and about the same as the grid-anode transconductance of a conventional amplifier tube having the same cathode area and fineness of electrode structures. It is thus apparent that a considerable increase in effective transconductance is obtainable from this amplifier circuit if $g_{15, 13} R$ can be made to approach unity. This is not difficult for low-frequency amplifiers nor is it difficult within limits for tunable narrow-band radio-frequency amplifiers when there is substituted for resistor R an impedance network 19 which has a uniform resistance over the frequencies to which the network is tunable.

Since the second anode voltage E_p and the first anode voltage E_2 are 180 degrees out of phase, the circuit of Fig. 2 may be used to obtain push-pull output with high gain. To make voltage E_p and voltage E_2 equal in magnitude, the value of impedance Z should be chosen so that the gain as obtained from Equation 11 is the same as that obtained from Equation 5. In the arrangement just described, the impedance network 19 and the virtual cathode formed between electrodes 13 and 15 comprise means including the impedance network for maintaining the voltage of the output circuit of the anode 16 in phase with the voltage of the input circuit comprising input-circuit terminals 17, 17 and 180 degrees out of phase with the voltage of the output circuit of the anode 13.

By way of example, the circuit of Fig. 2 has been found to operate satisfactorily as a cascade amplifier with the following constants:

$$g_{12, 13} = 1800 \text{ micromhos}$$

$$g_{12, 16} = 170 \text{ micromhos}$$

$$g_{13} = 110 \text{ micromhos (self conductance)}$$

$$50 \quad g_{13, 16} = 85 \text{ micromhos}$$

$$g_{15, 13} = 800 \text{ micromhos}$$

$$g_{15, 16} = 1650 \text{ micromhos}$$

$$R_1 = 1120 \text{ ohms (input resistance of network 19)}$$

$$R_2 = 100,000 \text{ ohms (resistance of resistor 20)}$$

55 The effective value of the first anode resistance R for this circuit is the parallel combination of the 1120-ohm and 100,000-ohm resistances and the self-resistance $(1/g_{13})$ of electrode 13 and calculates to be 987 ohms. This makes $g_{15, 13} R$ equal to 0.788, which is a value sufficiently less than unity, to give fair stability yet large enough to give a satisfactory gain. Substituting the foregoing values in the bracketed part of Equation 11 indicates that an effective transconductance between the first control electrode and the second anode of 14,400 micromhos is obtained.

70 For high-frequency operation of the amplifiers of Figs. 1 and 2, it is highly desirable that the vacuum tube 10 have satisfactory interelectrode shielding. One structure suitable for high-frequency use is shown schematically in cross-section in Fig. 3 in which cathode 11 has beam-forming baffles 25, 25 on either side thereof, while control electrode 12 is a conventional type of 75 control grid. Anode 13 preferably is formed of

spaced arcuate members of nonpermeable material adapted to collect all electrons returned from the virtual cathode formed just inside of control electrode 15, thereby to prevent such electrons from being returned to and dissipated at screen grid 14. Thus, the screen grid 14, which is disposed between control electrode 12 and anode 13, inhibits feedback to the input circuit in the amplifiers of both Figs. 1 and 2. The control electrode 15 preferably is of small pitch and wire size having supporting rods 26, 26 located on the axis of the beam in order to impart the correct trajectories to the electrons, some of which are turned back, as indicated by the dotted lines. The screen grid 24 between control electrode 15 and anode 16 is provided for a conventional purpose and is of the usual screen construction, while the anode 16 consists of two flat opposed plates, such as those used in the type 6AB7 and 6AC7 vacuum tubes, to reduce output capacitance. 20

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention. 25

What is claimed is:

30 1. An amplifier comprising, a vacuum tube having at least a cathode, a first control electrode, a first anode, a second control electrode, and a second anode, an anode circuit coupled to said second anode and said cathode, an input circuit coupled to said cathode and said first control electrode, an output circuit coupled to said cathode and said first anode and including a two-terminal impedance network having a substantially uniform resistance over a desired frequency band, means coupling said second control electrode to said first anode, and means for reflecting a negative resistance across said output circuit which tends to cancel the resistance thereof and the dynamic first anode-cathode self-resistance 45 comprising means providing a negative transconductance between said second control electrode and said first anode.

2. An amplifier comprising, a vacuum tube having at least a cathode, a first control electrode, a first anode, a second control electrode, and a second anode, an anode circuit coupled to said second anode and said cathode, an input circuit coupled to said cathode and said first control electrode, an output circuit coupled to said cathode and said first anode and including a two-terminal impedance network having a substantially uniform resistance over a desired frequency band, means for deriving a potential from said first anode and for applying it with the same 55 polarity to said second control electrode, and means for reflecting a negative resistance across said output circuit which tends to cancel the resistance thereof and the dynamic first anode-cathode self-resistance comprising means providing a negative transconductance between said second control electrode and said first anode. 60

3. An amplifier comprising, a vacuum tube having at least a cathode, a first control electrode, a first anode, a second control electrode, and a second anode, an anode circuit coupled to said second anode and said cathode, an input circuit coupled to said cathode and said first control electrode, an output circuit coupled to said cathode and said first anode and including a two- 75

terminal impedance network having a substantially uniform resistance over a desired frequency band, and means for reflecting a negative resistance across said output circuit which tends to 5 cancel the resistance thereof and the dynamic first anode-cathode self-resistance comprising means providing a negative transconductance between said second control electrode and said first anode of such value that the product of said 10 transconductance and said resistance of said network approaches but is less than unity.

4. An amplifier comprising, a vacuum tube having at least a cathode, a first control electrode, a first anode, a second control electrode, and a second anode, an input circuit coupled to 15 said cathode and said first control electrode, a first output circuit coupled to said cathode and said first anode and including a two-terminal 20 impedance network having a substantially uniform resistance over a desired frequency band, an anode circuit coupled to said cathode and said second anode, means coupling said second control electrode to said first anode without substantial phase shift, and means for reflecting a 25 negative resistance across said first output circuit which tends to cancel the resistance thereof and the dynamic first anode-cathode self-resistance comprising means providing a negative transconductance between said second control 30 electrode and said first anode.

5. An amplifier comprising, a vacuum tube having at least a cathode, a first control electrode, a first anode, a second control electrode, and a second anode, an input circuit coupled to 35 said cathode and said first control electrode, a first output circuit coupled to said cathode and said first anode and including a two-terminal impedance network having a substantially uniform resistance over a desired frequency band, a second output circuit coupled to said cathode and said second anode, means for reflecting a negative resistance across said first output circuit which tends to cancel the actual resistance 40 thereof and the dynamic first anode-cathode self-resistance comprising means coupling said second control electrode to said first anode without substantial phase 45 shift, and means including said network for maintaining the voltage of said

second output circuit in phase with the voltage of said input circuit and 180 degrees out of phase with the voltage of said first output circuit.

6. An amplifier comprising, a vacuum tube having at least a cathode, a first control electrode, a first anode, a second control electrode, and a second anode, an input circuit coupled to 5 said cathode and said first control electrode, a first output circuit coupled to said cathode and said first anode and including a two-terminal 10 impedance network having a substantially uniform resistance over a desired frequency band, a second output circuit coupled to said cathode and said second anode, means for reflecting a negative resistance across said first output circuit 15 which tends to cancel the actual resistance thereof and the dynamic first anode-cathode self-resistance comprising means coupling said second control electrode to said first anode without substantial phase shift, and means including 20 said network for maintaining the voltage of said second output circuit in phase with the voltage of said input circuit and 180 degrees out of phase with the voltage of said first output circuit, the effective resistance of said first output circuit 25 being so proportioned with respect to the impedance of said second output circuit that the voltage of said first output circuit substantially equals the voltage of said second output circuit.

7. A regenerative amplifier comprising, a vacuum tube having at least a cathode, a first control electrode, a first anode, a second control electrode, and a second anode, an anode circuit coupled to said cathode and said second anode, an input circuit coupled to 35 said cathode and said first control electrode, an output circuit coupled to said cathode and said first anode and including a two-terminal impedance network having a substantially uniform resistance over a desired frequency band, and means for obtaining 40 regeneration comprising means for developing a negative transconductance between said second control electrode and said first anode, and means coupling said second control electrode to said first anode without substantial phase 45 shift.

ROBERT L. FREEMAN.
